UNITED STATES PATENT OFFICE.

LORIN OTTO MILLER, OF DUNKIRK, INDIANA, ASSIGNOR OF TWO-THIRDS TO MARK M. MORAN AND JAMES R. FLEMING, BOTH OF PORTLAND, INDIANA.

MIXING DEVICE FOR INTERNAL-COMBUSTION ENGINES.

1,344,706.

Specification of Letters Patent. Patented June 29, 1920.

Application filed February 14, 1920. Serial No. 358,789.

To all whom it may concern:

Be it known that I, LORIN O. MILLER, a citizen of the United States, residing at Dunkirk, in the county of Jay and State of Indiana, have invented certain new and useful Improvements in Mixing Devices for Internal-Combustion Engines, of which the following is a specification.

This invention relates to improvements in mixing devices for internal combustion engines.

An important object of the invention is to provide a device adapted for insertion intermediate the carbureter and the intake manifold of an internal combustion engine which will materially assist in the thorough commingling of the gaseous vapors from the carbureter.

I am aware that numerous devices of this type have been constructed, but many of these devices provide for the intake of additional air. Furthermore, many of these devices depend entirely upon a screen for the breaking-up of the gaseous vapors. I have found that the use of the screen alone in such a device will not accomplish the desired result with as great efficiency as a device wherein cross arms are arranged in the path of the vapors forwardly of the screen, these cross arms being inclined toward the screen and meeting at a common central point. I have found, furthermore, that the efficiency of the device is increased if the cross arms are perforated preventing the formation of vacuums to the rearward side thereof and are tapered against the direction of flow of the gases.

In the accompanying drawings wherein for the purpose of illustration is shown a preferred embodiment of my invention and wherein like numerals designate like parts throughout.

Figure 1 is a perspective view of an internal combustion engine showing my apparatus inserted between the carbureter and intake manifold thereof.

Fig. 2 is a sectional view taken through the mixer and its attached parts, taken on the line 2--2 of Fig. 1.

Fig. 3 is a section on the line 3--3 of Fig. 2.

Fig. 4 is a section on the line 4--4 of Fig. 2, and

Fig. 5 is a section on the line 5--5 of Fig. 3.

Referring now more particularly to the drawings, the numeral 10 indicates a suitable plate provided with a central circular aperture 11. The metal surrounding the aperture is provided with an annular groove 12 within which is fitted a screen 13.

This screen is curved in the direction for passage of the gas when the plate 10 is in its proper position, as shown in Fig. 2. A retaining ring 14 is provided and inserted in the groove for the purpose of preventing accidental removal or displacement of the screen 13.

Cross arms 15 are provided. These cross arms are arranged upon the side of the screen 13 toward the incoming gases and are preferably four in number and taper the small sides thereof facing toward the incoming gases. These arms are arranged in a plane at an angle to the body plane of the plate 10 and meet centrally of the aperture 11. By inspecting Fig. 2, it will be seen that these arms incline in the direction of curvature of the screen 13. Apertures 16 are formed at each of the arms 15, the apertures being enlarged at each end as at 17. At the junction of the arms 15, an enlarged aperture 18 similar to the apertures 16 is provided.

The sides of the plate 10 are provided with notches 19 adapted to receive bolts 20 which bolts also pass through the flanges of the carbureter 21 and the intake manifold 22, gaskets being provided intermediate the carbureter and the plate 10 and the intake manifold.

In the operation of my device, the gases drawn from the carbureter by the suction of the engine, are caused to circulate around the cross arms 15 in passing them and are thoroughly commingled. The purpose of the apertures formed in the cross arms is to allow a certain percentage of the gases to pass through said apertures to form a plurality of currents which will counteract any tendency to create a vacuum and which will commingle with the gases passing along the tapered sides of the arms and thoroughly mix them. A further commingling of the gases is accomplished by the screen 13 which thoroughly scatters the gases and disperses them uniformly through the area of the intake manifold.

I have found that the curved form of screen is the most efficient which may be used

for the commingling of the gases. I have also found that the inclined cross arms aid materially in the commingling of the gases due to the peculiar circulation of currents 5 caused thereby and that these inclined cross arms gives a much higher coefficient of efficiency than cross arms which are arranged straight across or in the plane of the plate. This is doubtless caused by the fact that when 10 the cross bars are arranged straight across, the central portions thereof lie so far from the screen 13 that the proper circulation of currents is not formed. It will of course be understood that the screen 13 acts in a measure as a baffle and causes an increased circulation of the gases intermediate the screen and the cross arms 15. It has further been found that the cross arms when inclined and not perforated are not as efficient as the perforated cross arms of the same type, as the 20 arms have a tendency to the formation of vacuums in which the liquids of the vapor will precipitate.

What I claim is:

- 25 1. A mixing device for internal combustion engines, comprising a plate adapted for insertion intermediate the carbureter and intake manifold of the engine, said plate being provided with a central aperture, a screen arranged within said aperture and convexed in the direction of flow, cross arms extending into said aperture intermediate said carbureter and said screen, said cross arms being spaced from said screen and provided with 30 apertures extending in the direction of flow of the gases.
2. A mixing device for internal combustion engines, comprising a plate adapted for insertion intermediate the carbureter and intake manifold of the engine, said plate being provided with a central aperture, a screen arranged within said aperture and convexed in the direction of flow, cross arms extending into said aperture intermediate 35 said carbureter and said screen, apertures formed in said cross arms, said apertures extending in the direction of flow of the gases, said cross arms inclining toward a common center and 40 being joined centrally.
- 45 50

3. A mixing device for internal combustion engines, comprising a plate adapted for insertion intermediate the carbureter and intake manifold of the engine, said plate being provided with a central aperture, a screen arranged within said aperture and convexed in the direction of flow, cross arms extending into said aperture intermediate said carbureter and said screen, said cross arms being inclined in the direction of flow of the vapor from said carbureter, meeting and being joined at a common center and spaced from said screen, each of said cross arms having apertures extending therethrough in the direction of flow of the vapors from the carbureter.

4. A mixing device for internal combustion engines, comprising a plate adapted for insertion intermediate the carbureter and intake manifold of the engine, said plate being provided with a central aperture, a curved screen arranged within said aperture, and cross arms carried by said plate, said cross arms being inclined in the direction of curvature of said screen and provided with apertures extending therethrough in the direction of flow of the vapors from the carbureter, the screen and cross arms being spaced from each other.

5. A mixing device for internal combustion engines, comprising a plate adapted for insertion intermediate the carbureter and intake manifold of the engine, said plate being provided with a central aperture, a curved screen arranged within said aperture, and cross arms carried by said plate, said cross arms being inclined in the direction of curvature of said screen and provided with apertures extending therethrough in the direction of flow of the vapors from the carbureter, said cross arms being tapered and having the small sides thereof arranged remote from said screen and spaced therefrom.

In testimony whereof I affix my signature in presence of two witnesses.

LORIN OTTO MILLER.
